[57] **CLAIM**

The ornamental design for a dispenser support, as shown and described.

DESCRIPTION

FIG. 1 is a perspective view of a dispenser support showing my new design.

FIG. 2 is a front view thereof.

FIG. 3 is a right side view thereof, the left side view being a mirror image thereof.

FIG. 4 is a back view thereof.

FIG. 5 is a top view thereof.

FIG. 6 is a bottom view thereof; and,

FIG. 7 is a perspective view thereof in one possible environment.

The broken-line showing of environmental structure in FIG. 7 is for illustrative purposes only and forms no part of the claimed design.
